UNITED STATES PATENT OFFICE.

FRED HOTCHNER, OF LOS ANGELES, CALIFORNIA.

FLASHING AND REGULATING APPARATUS FOR DISCHARGE-TUBE DISPLAY.

Application filed March 9, 1927. Serial No. 174,063.

This invention relates to electric displays of the discharge tube type made into electric signs, building ornamentation, stage effects, etc. It provides means and apparatus for illuminating, regulating the current flow in and flashing such displays, said means overcoming the disadvantages now met due to the inherent electrical characteristics of discharge tubes, reducing the cost, improving the effects, simplifying and increasing the range of application of such displays.

Discharge tube installations as now made are very cumbersome and expensive and greatly limited in their applications as compared with incandescent lamp installations. This is due to the limitations arising from the characteristics of the tubes. The most important characteristics of discharge tubes are as follows:

20 The variable resistance of the tube over a single cycle.

The variable resistance of the tube over the period of its life.

25 The capacity effect in the tube due to the energy of ionization.

The distributed capacity effect due to the conductivity of the walls.

The tendency of the arc to pinch out.

These characteristics and certain conditions met in practice give rise to numerous difficulties met in the assembling of a number of tubes into a display.

In practice the variation between several tubes in the same display is enormous. No 30 two tubes will be the same in their electrical characteristics even if made the same and at the same time. As the tubes are bent into the shape of letters and figures the cross sections are not uniform. The length varies

35 and the configuration is such as to cause static and inductive effects that can not be measured and are always different. Tubes containing different gases are used together. Tubes of different age will be found together

40 in the same display. It can be easily understood why attempts at balancing or compensating for the effects of the tubes have all failed.

Attempts at operating a number of tubes 45 in parallel have also been made without success. As the tubes hold a certain amount of energy during the cycle of current change it is to be expected that currents will circulate between the tubes. This appears to be 50 the case from the evidence of the experiments and might easily be the reason why a suc-

cessful system of operating tubes in parallel with the use of inductive or capacitive regulators has not been found. The circulating currents might be expected to have much the same effect as surges on transmission lines. Voltage peaks will exist that will rupture condensers and break down the insulation. As oscillation is easily set up no matter how carefully designed a parallel system might be; if one of the many variables changes, two or more tubes might start to oscillate. As I explain below, in this invention the use of inductances or capacitances has been dispensed with, thereby 60 eliminating anything that tends to exaggerate the oscillating effect; and the regulating device used has in itself a certain power to suppress oscillations.

Because of the variable resistance of the tubes during a cycle of current change the electrical problems involved are unusually difficult. The resistance of the tube is very high before current flow starts, and as soon as current flows the resistance falls to a very low value, so low in fact, that were the potential to be maintained after the arc started the tube would be destroyed or seriously damaged by the current. The method of operating discharge tubes in practice at the present time is to place a single tube or several tubes in series on a single transformer of such poor characteristics that the potential across the terminals falls as the current increases. Somewhat the same effect is also secured by using a transformer of characteristics approaching that of standard power transformers and inserting a choke coil in the system, preferably in series with the primary.

It is obvious that on such a current source parallel operation is impossible as the tube which strikes an arc first will immediately lower the potential across the other tubes below the arcing voltage and will also draw an excessive current.

The objects of my invention, therefore, are to provide means of operating a number of tubes in parallel which may be of any desired length, of any current requirements and have any inductive or static characteristics incidental to its manufacture.

Another object is to prevent oscillations between the tubes and dangerous rises of voltage.

11 A further object is to prevent the flickering incidental to oscillations.

A further object is to reduce the expensive insulation required for high voltage operation by placing tubes in parallel and operating at a lower voltage.

5 A further object is to make use of transformers of characteristics approaching those of standard power transformers.

Another object is to provide means of 10 flashing the tubes separately on a parallel operating system.

Further objects will appear as the description proceeds.

Fig. 1 is a diagram showing the principal features of this invention.

15 Fig. 2 shows a modification of this invention in which I use a tap on the transformer for lighting the filaments instead of a separate transformer.

20 Fig. 3 shows a further modification of this invention in which I distribute the tubes into two sets, each set working on one side of the cycle.

In the drawings, numerals 2, 3, 4 and 5, 25 Fig. 1, are discharge tubes which may be of any length desired or of any configuration. They may also be of different current characteristics or may contain different gases. Numerals 6, 7, 8 and 9 are thermionic tubes of the half-wave rectifying type. Each 30 thermionic tube has a plate 14, 15, 16 and 17 which is connected to one terminal of the corresponding discharge tube by the wires 10, 11, 12 and 13. Each thermionic tube has a filament, 18, 19, 20 and 21, one terminal of 35 each filament being connected to the wire 22 which extends to one terminal of the secondary 23 of the step-up transformer 24. The other terminal of the secondary 23 connects to the common return wire 25 which extends 40 to one terminal on each of the discharge tubes thus completing the parallel circuit.

The filament lighting circuit is thru the filaments and the wire 22 which connects to one terminal of the filament transformer 45 secondary 26, the wire 28 which extends to the collector brush 29 of the flasher 30, the wires 31, 32, 33 and 34 connecting to the 50 flashing brushes 35, 36, 37 and 38 and extending to the other terminals of the filaments 18, 19, 20 and 21, thru the variable resistances 39, 40, 41 and 42.

In practice the transformer 24 is designed to develop a voltage high enough to light the longest tube that would be used, and to pass 55 the maximum current that it will be operated for with as little drop across the terminals as is consistent with good design. This is in contrast with the present practice of providing transformers of high drop, or 60 of high choking effect.

When the display is installed each variable resistance is adjusted until its corresponding discharge tube is at the right degree of illumination. As the current passing thru 65 the discharge tube is dependent on the elec-

tron flow from the filaments of the thermionic tubes, the discharge tubes will always light the same and will not change except over a long period of time due to various aging tendencies of the two tubes.

If the tubes change by age the resistances are readjusted and the display brought back to normal.

Should a short circuit occur in the tube, or across the tube terminals the thermionic 75 tube continues to serve as a regulator and protects the transformer from a rush of current.

As current can flow only in one direction thru the thermionic tube, oscillations between the tubes can not occur as oscillations to have any effect must be sustained longer than one half cycle.

By designing the transformer with a minimum of choking effect the tendency to oscillate is further reduced.

The operation of the flasher 30 illuminates and extinguishes the filaments of the thermionic tubes. When the electron flow is interrupted the current to the discharge tube is cut off without an arc. The flashing tube does not disturb any of the others, and all tubes will burn the same regardless of how many others are lighted. This method of 85 flashing is a decided improvement over the present practice which is to put the different tubes that are to be flashed on separate transformers and flash the primaries. The current interrupted by my flasher is very small as compared with the power interrupted and 90 the burn on the brushes will therefore be very little.

While I have shown a separate transformer in Fig. 1 for the illumination of the filaments, this is not necessary as a tap 43, 105 Fig. 2 can be taken off of the secondary 23 to provide the low potential current for the filaments. Another method would be to provide an extra coil on the same core as the secondary 23.

In Fig. 3 I show a modification of this invention in which the tubes are divided into two groups and each group is connected to work on one half of the cycle, thus making use of the entire output of the transformer. 110 The discharge tubes 44 and 45 are connected in series each with one of the thermionic tubes 46 and 47 and the resistances 48 and 49 on one side of the system. They are carried thru the flasher 50 and to the tap 51 on one side of the secondary 52 of the transformer 53. The tubes 54 and 55 are connected in series with the regulating tubes 56 and 57 and the resistances 58 and 59 and thru the flasher 60 to the tap 61.

Having thus described my invention and the manner of constructing and using the same, altho without attempting to set forth all of the forms in which it may be made, or all of the modes of its use, I claim:

1. A discharge tube in series with a thermionic regulating tube.
2. A discharge tube in series with a thermionic regulating tube of the half-wave rectifying type.
3. A discharge tube in series with a thermionic regulating tube, said regulating tube having a plate and a filament; and means of regulating the temperature of said filament.
4. A discharge tube in series with a thermionic regulating tube, said regulating tube having a plate and a filament; and means of flashing said filament.
5. A discharge tube in series with a thermionic regulating tube and means to impress an alternating potential across both said tubes, said potential maintaining the sine wave independently of the current flowing thru said tubes.
6. A plurality of discharge tubes, each in series with a thermionic regulating tube and all of said series of tubes being in parallel.
7. A plurality of discharge tubes, each in series with a thermionic regulating tube of the half-wave rectifying type, and all of said series of tubes being in parallel.
8. A plurality of discharge tubes, each of said discharge tubes being in series with a thermionic regulating tube, all of said series of tubes being in parallel; each of said thermionic tubes having a plate and a filament and means to regulate the temperature of each of said filaments independently.
9. A plurality of discharge tubes, each of said discharge tubes being in series with a thermionic regulating tube and all of said series of tubes being in parallel; each of said regulating tubes having a plate and a filament and means of flashing said filaments independently.
10. A plurality of discharge tubes, each in series with a thermionic regulating tube and means to impress an alternating potential across all of said series of tubes, the source of said potential maintaining said potential in substantially a sine wave form regardless of the performance of said tubes.
11. A plurality of discharge tubes in parallel and means to suppress oscillations between said tubes.
12. A plurality of discharge tubes in parallel, means to flash said discharge tubes independently and means to suppress oscillations between said tubes.
13. A discharge tube and non-inductive, non-capacitive means to regulate the current passing thru said tube.
14. A plurality of discharge tubes in parallel and separate non-inductive, non-capacitive means in series with each of said tubes to regulate the current passing thru each of said tubes independently.
15. A plurality of discharge tubes, each tube being in series with a regulating thermionic tube and all of said sets of tubes being in parallel on the secondary of a step-up transformer, and means to interrupt the flow of electrons in any one or more of said thermionic tubes to extinguish the corresponding discharge tube or tubes.
16. A plurality of discharge tubes of different current consumption, each of said tubes being in series with a thermionic regulating tube and all of said series being in parallel.
17. The method of operating discharge tubes in parallel which consists of connecting a plurality of discharge tubes, each of said tubes being in series with a thermionic regulating tube, in parallel across a source of current that maintains a relatively true sine wave of potential across the terminals of all of said series of tubes.
18. The method of operating discharge tubes in parallel which consists of connecting in series with each of said tubes means to limit the flow of current to a maximum value and to one direction only.
19. A plurality of discharge tubes, each of said discharge tubes being in series with a thermionic regulating tube of the hot filament type and all of said series being in parallel across the terminals of a high-voltage transformer, and a low voltage transformer connected with the circuit of said high voltage transformer for illuminating the filaments of said thermionic regulating tubes.
20. A plurality of discharge tubes, each of said discharge tubes being in series with a thermionic regulating tube of the hot filament type and all of said series being in parallel across the terminals of a high-voltage transformer, and means in said transformer to provide a current of low potential for illuminating the filaments of said thermionic regulating tubes.
21. A plurality of discharge tubes, each in series with a half-wave rectifying regulator, and all of said series being in parallel, said series being divided into two groups and connected to work on opposite sides of the cycle.

Signed at Los Angeles, California, this 4th day of March, 1927.

FRED HOTCHNER.
